UNITED STATES PATENT OFFICE.

WALKER E. MARSHALL, OF SPRINGFIELD, OHIO, ASSIGNEE OF FORTY-FIVE PER CENT TO IRA M. EULITT, OF SPRINGFIELD, OHIO.

VALVE.

Application filed September 19, 1919. Serial No. 324,994.

To all whom it may concern:

Be it known that I, WALKER E. MARSHALL, a citizen of the United States, and a resident of the city of Springfield, county of Clark 5 and State of Ohio, have invented certain new and useful Improvements in Valves, of which the following is a specification.

My invention relates to new and useful improvements in an automobile attachment and 10 has for its object the provision of a device which will prevent the operation of an automobile, without the consent of the owner.

Other objects will appear hereinafter.

The invention consists in the combinations 15 and arrangements of parts hereinafter described and claimed.

The invention will be best understood by reference to the accompanying drawings, forming a part of this specification, and in 20 which,

Fig. 1 is a side elevation of a gasoline engine embodying my invention,

Fig. 2 is a side elevation of my invention,

Fig. 3 is a top plan view of my invention,

Fig. 4 is a sectional view taken on substantially line 4—4 of Fig. 3,

Fig. 5 is a sectional view taken on substantially line 5—5 of Fig. 2,

Fig. 6 is a sectional view taken on substantially line 6—6 of Fig. 5,

Fig. 7 is a sectional view taken on substantially line 7—7 of Fig. 5,

Fig. 8 is a sectional view taken on substantially line 8—8 of Fig. 5,

Fig. 9 is a sectional view taken on substantially line 9—9 of Fig. 8,

Fig. 10 is a perspective view of a valve member of my invention,

Fig. 11 is a top plan view of a modified 40 form of my invention,

Fig. 12 is a sectional view taken on substantially line 12—12 of Fig. 11,

Fig. 16 is a side elevational view of the 50 modified form of my invention,

Fig. 17 is a sectional view taken on substantially line 17—17 of Fig. 13,

Fig. 18 is a sectional view taken on substantially line 18—18 of Fig. 13,

Fig. 19 is a fragmentary sectional view 55

of the modified form of my invention showing the double valve connection.

The approved form of construction comprises a conduit in the form of a housing 20, having ports 21 and 21' disposed at 60 opposite sides and communicating with the interior of the housing 20. Flanges 22, preferably made integrally with the housing 20, surround and project outwardly from the ports 21 and 21'. The housing 20, is open 65 at one end 23, and interiorly threaded to engage the threaded surface of a cap 24, which is adapted to close the open end of the housing 20. The cap 24, has a laterally projecting flange 25 which is adapted to seat upon 70 the wall of the housing 20, and tightly engage the same.

Projecting from the interior surface of the cap 24, is a post or pin 26 and projecting 75 inwardly from the inner surface of the closed end 27 of the housing 20, is a pin or post 28 which is preferably made integral with the wall of the housing 20. These pins 26, and 28 project inwardly from the center of the end and the cap and are spaced apart 80 at their inner ends. A curved metallic valve member 29, is positioned within the housing 20, the periphery of which is struck on a circle having the same diameter as the interior surface of the housing 20, so that 85 the member 29 may lie in engagement, throughout its entire surface, with the inner surface of the housing 20. Projecting inwardly from the opposite ends of the member 29, are arms 30, which may be connected to the same by being formed dove-tailed and secured in a dove-tailed slot 31. Positioned 90 rotatably upon the pins 28 and 26 are arms 32 which project outwardly and are securely fastened to the inwardly projecting arms 30, 95 by means of bolts 33. Each of the arms 32 is provided with a slot in which one of the bolts 33 may be permitted to ride. As clearly shown in Fig. 5, the arms 32 and 30 overlap. Therefore, it appears evident that 100 upon tightening the bolt 33, which is threaded into the member 30, the arms 32 and 30 will be retained in immovable relation to each other. The purpose of this connection between the members 30 and 32, is to afford a means of retaining the member 29 in close engagement with the inner wall of 105 the housing 20, the adjustments being made whenever the necessity arises from wear of the parts involved.

Interposed between the under surface of the lower member 32, and the inner surface of the member 24, upon the member 26 is a spirally formed torsional spring 34, one end 35 of which engages a stop block 36, which projects from the inner surface of the member 24. The other end 37, of the member 34, engages a stop block 38 which is the head of a pin 40, which is inserted through 10 the member 32 and extends upwardly so as to engage between the teeth of a gear 39, which is rotatably mounted upon the member 26, so as to engage the upper surface of the member 32. A retaining member 41, 15 which is formed tubular at its opposite ends embraces or receives the inwardly projecting ends of the members 26 and 28, and thereby retains the inner ends of the members 32 in their spaced relation. Projecting laterally from the central portion of 20 the member 41, is a post 42 upon which is positioned one end of a spiral spring 43, the opposite end of the member 43 being positioned upon a post 44, which projects inwardly 25 from the inner surface of the member 29. The purpose of the spring 43, is to afford a means of adjusting the member 20 upon release of the friction between members 32 and 30. The spring 43 serves 30 to push the member 29 outwardly so that when the member 29 is adjusted so that it is not spaced its maximum distance from the member 41, the spring 43 will be compressed.

Projecting inwardly from the inner surface of the cap 24, adjacent one side thereof, is a cup shaped member 45, an opening 45' being provided in the member 24, registering with the cup member 45. Projecting through the inner surface of the member 45, is a bolt 46 which is adapted to be secured in its assembled position to a gear wheel 48, which meshes with the gear 39. Projecting outwardly from the member 48, 45 is a cup shaped member 49. Securely fastened within the cup shaped member 45, by means of a bolt 47, is a guard or tumbler 50, this tumbler being adapted to extend into the opening 45', in the member 24. A 50 cup or barrel 51 is provided, which is adapted to seat in the opening 45', which is formed in the member 24. A key hole 52, is provided in the member 51 for the insertion of a key therein, which is adapted 55 to engage in a recess, formed in the cup shaped member 49 and thereby afford a means of rotating the gear 48. This member 51 is secured in its assembled position in the opening 45' by means of a bolt 53, 60 which is threaded into the member 51 and adapted to slidably engage in a slot 54, formed in the member 45 adjacent the inner surface of the cap 24.

Threaded into the housing 20, is a nipple

55, which is open at its inner end. Mounted 65 within the nipple 55, is a rod 56 which projects through an opening in the wall of the housing 20, and extends into the interior thereof. Securely mounted upon the member 56, adjacent the inner end thereof and 70 within the nipple 55, is a collar 57. Positioned upon the member 56, within the nipple 55, and interposed between the end of the nipple 55 and the collar 57, is a spiral spring 58, as clearly appears from Fig. 6. 75 Upon withdrawing the member 56 from the housing 20, the spiral spring will force the member 56 back into the housing 20, upon release of the withdrawing force, providing trigger mechanism in the form of a catch 80 which will engage the valve member 29 when the same is turned to open position. As is clearly shown in Fig. 1, the rod 56 is provided with a flexible member, such member to extend to a convenient position 85 with respect to the driver's seat for releasing the catch for permitting the closure of the valve.

Formed adjacent one end of the member 29, at one edge thereof is a recess 59, (Fig. 90 6) in which the member 56 is adapted to engage, when in operative position as clearly seen in Fig. 5. Projecting inwardly through the wall of the housing 20 and extending a distance into the interior, is a 95 stud 60, which is adapted to engage the member 29 when the same is moved to operative position, or to that position in which the lower port 21' is closed (see Fig. 6).

Mounted upon the inner face of the member 24, is a pawl 61, with which cooperates a spring 62 also mounted upon the member 24. The member 62 has a tendency to retain the member 61 in outwardly extending position. Formed in the inner surface of 100 the member 20, adjacent the end on which member 24 is secured, are recesses 63, in which the pawl 61 is adapted to engage when projecting outwardly. The construction is such that upon the turning on 105 of the cap 24, the pawl engages against the interior surface of the member 20 and is flexed inwardly so as to be in recess 64, formed in the cap 24. Upon the member 61, passing the recesses 63, the pawl will 115 respond to the tension of the spring 62 and engage in these recesses. It is thus seen that upon the threading on of the cap 24, the same cannot be removed by backward 120 threading without first turning the pawl 115 into the recess 64. To do this, it is of course necessary to operate in the interior of the housing 20, through either of the ports 21 or 21'. The manipulation of this pawl or a turning of either of the gear wheels 39 or 125 48, is further rendered difficult by the presence of a disc 65, which is mounted upon the member 46 and retained in position by

a nut 66. An opening is provided centrally in the member 65 for the passage of the member 41 therethrough.

My invention is adapted to be used in conjunction with automobiles and to afford a means of preventing theft of the same. The invention is interposed between the carburetor 67 and the intake pipe 68 of the manifold of the engine. My invention is adapted to close communication between the carburetor and the intake pipe of the manifold and securely lock the same in such closed relation until a key specially designed for the particular device used is inserted in the keyway for opening communication between the carburetor and manifold.

When the communication is established between the carburetor and manifold, the port 21' will be open and the member 29 will be in the position shown in Fig. 5, and it will be noticed that the member 56 is there shown engaging the member 29 in the slot

59. In order to place the member 29 in this position, it was necessary to rotate it 90 degrees approximately, within the housing 20. The member 56 automatically engages in the opening 59, upon the rotating of the member 29 a sufficient distance. Upon disengaging the member 56 from the member 29, the member 29, responding to the strain exerted by the spring 34, as shown in Fig. 6, will quickly move in the direction indicated by the arrow, and thereby close the port 21'. The member 60, is provided for the purpose of preventing the member 29 from moving beyond the opening or port, as will be readily understood.

When the device is assembled upon the engine and the valve 29 has moved to closing position, a key is inserted in the key hole 52. Each particular device is specially constructed so far as the tumbler is concerned and consequently has its own individual key. The key of course turns the member 51, and also engages the member 49 and thereby rotates the gear 48, which in turn rotates the gear 39, which carries with it the lower arm 32 and thereby moves the valve 29. I have shown my invention applied to a gasoline engine and disposed intermediate the carburetor and the manifold. However, my device may be applied to a gasoline engine at any suitable place intermediate the manifold and gasoline supply tank.

In the modified form (Figs. 11 to 19) I provide a pair of valves, which are connected together and operate simultaneously. One of the valves, that is the outer valve is disposed in a slot 70', (Fig. 17) which is formed in the wall of the housing 20. Of course, in the devices in which the slot 70' (Fig. 17) appears, the wall of the housing is made thicker than otherwise. The outer valve 70, which rides in the slot 70' (Fig.

17), is connected to the inner valve 29 by connecting means comprising a bolt 72 (Fig. 19) threaded into the valve 70. The inner end of the bolt 72, is constructed to form a cup 71 in which is positioned a head 74 of a bolt 73, which is threaded into the valve 29, a recess being provided in the inner end of the bolt 73 for affording a means of turning the same with a screw driver or other like instrument. Positioned in the cup 71, and engaging the inner face of the member 74, is a spiral spring 75. It is apparent that the pressure of the valve 70, against the outer wall of the chamber in which it rides, may be regulated by adjustment of the member 73. A slot 76, is provided in the inner portion of the wall of the housing 20 in which the connecting means joining the two valves is adapted to slide. The valve 29, is connected to the valve 70 at two ends adjacent one of the sides by the means already described.

The valve 70, is inserted into the slot 70' from the end of the device and consequently another cap 77 is provided, which is constructed similar to the cap 24, having a pawl formed thereon, adapted to engage in recesses formed in the inner wall of the housing. In the modified form, adjacent the cap 24, I have secured to the inner wall of the housing 20, a leaf spring 78, which is adapted to be flexed upon the opening of the valve and consequently under strain to restore the valve to closing position. This spring 78, may be used either separately or in conjunction with the spiral spring 34.

In my modified form, I have provided a device which will be effective even though one of the valves should leak, as the additional valve affords a secondary safeguard.

The valve, which I have shown in the modified form, may be used generally whenever an instantaneously closing valve may be required. This feature of this valve is apparent inasmuch as the valve instantly closes upon retracting or withdrawing the member 56 from engaging position with the valve. In Fig. 17, the member 56 is shown as engaging both the valve 70 and the valve 29.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. In combination, a conduit for feeding fuel to an internal combustion engine; valve

means for shutting off the flow of fuel through said conduit; key operated means for moving said valve means to open position; means normally urging said valve means to closed position; mechanism adapted to engage said valve means when the same are moved to open position; and means for releasing said mechanism.

2. In combination, a conduit for feeding fuel to an internal combustion engine of an automobile; valve means for shutting off the flow of fuel through said conduit; key operated means for moving said valve means to open position; means for normally urging said valve means to closed position; mechanism adapted to engage said valve means when the same are turned to open position; and means extending to a point adjacent the driver's seat for releasing said mechanism.
3. In combination, a pipe for feeding fuel into an internal combustion engine for an automobile; a housing interposed in said pipe and communicating therewith; a valve assembly occupying only a small portion of said housing for shutting off the flow of fuel therethrough; means normally urging the valve to closed position; key operated means in said housing for opening said valve; means for engaging said valve for holding the same in open position; and means located at a point convenient to the driver's seat by the actuation of which said holding means is released.

4. In combination, a pipe for feeding fuel to an internal combustion engine; a housing interposed in said pipe and communicating therewith; a valve assembly occupying only a small portion of said housing for shutting off the flow of fuel therethrough; key operated means in said housing for opening said valve; an automatically acting catch for holding said valve open; means operable from a point at a distance from the housing for releasing said catch; and a spring adapted to move said valve into closing position when said catch is released.

5. In combination, a pipe for feeding fuel to an internal combustion engine; a housing interposed in said pipe and communicating therewith; a valve assembly occupying only a small portion of said housing for shutting off the flow of fuel therethrough; key operated means in said housing for opening said valve; an automatically acting catch for holding said valve from closing when the valve is moved to open position; means operable from a point at a distance from the housing for releasing said catch; and a spring adapted to move said valve into closing position when said catch is released.

6. In combination, a pipe for feeding fuel to an internal combustion engine; a housing interposed in said pipe and communicating therewith; segmental valve means in said housing for shutting off the flow of fuel

through said pipe; revolvably mounted key operated means connected positively with said valve so as to rotate in unison therewith for opening said valve; and means operating independently of said key operated means permitting said valve to be turned to open position but preventing its return to closed position.

7. In combination, a pipe for feeding fuel to an internal combustion engine; a housing interposed in said pipe and communicating therewith; a shaft mounted in said housing; arms rotatably mounted on said shaft; a valve carried by said arms and adapted to slidably engage the inner periphery of said housing; key operable means connected with said valve to open same; and means yieldable while said valve is turned to open position, but unyieldable to prevent a return of said valve to closed position.

8. In combination, a pipe for feeding fuel to an internal combustion engine; a housing interposed in said pipe and communicating therewith segmental valve means slidably engaging the inner periphery of said housing for shutting off the flow of fuel through said pipe; revolvably mounted key operated means connected positively with said valve so as to rotate in unison therewith for opening said valve; an automatically acting catch which permits said valve to be turned to open position but prevents its return to closed position; means for releasing said catch; and yielding means connected to said valve, and adapted to move same into closing position when said catch is released.

9. In combination, a pipe for feeding fuel to an internal combustion engine; a housing interposed in said pipe and communicating therewith; a shaft traversing said housing; a valve swingably mounted on said shaft and adapted to slidably engage the inner periphery of said housing; a spring secured to said shaft and to said valve for normally urging same to closed position; a plunger yieldably projecting into said housing; key operated means for turning said valve over said plunger to open position; and means for withdrawing said plunger to permit said valve to assume closed position.

10. In combination, a pipe for feeding fuel to an internal combustion engine; a housing interposed in said pipe and communicating therewith; valve means for shutting off the flow of fuel through said pipe; revolvably mounted key operated means connected positively with said valve so as to rotate in unison therewith for opening said valve; means operating independently of said key operated means for holding said valve open; and yielding means adapted to turn said valve and said key operating means together for moving said valve into closing position when said catch is released and means for preventing a move-

ment of said valve beyond closed position.

11. In combination, a pipe for feeding fuel to an internal combustion engine; a housing interposed in said pipe and communicating therewith; valve means for shutting off the flow of fuel through said pipe; revolubly mounted key operated means connected positively with said valve so as to rotate in unison therewith for opening said valve; a catch acting automatically to hold said valve and said key operated means from movement into closing position; means for releasing said catch; means normally urging said valve and said key operating means toward closed position; and means for limiting the movement of said valve means toward closed position, thereby assuring return of said valve and said key operating means to original position.
12. In combination, a pipe for feeding fuel to an internal combustion engine for an automobile; a housing interposed in said pipe and communicating therewith; valve means in said housing slidably engaging the inner periphery thereof for shutting off the flow of fuel through said pipe; key operated means in said housing connected positively with said valve so as to move in unison therewith for opening the valve; a catch acting automatically to hold said valve and said key operated means from movement into closing position; and means operable from a point convenient to the driver's seat for releasing said catch.
13. In combination, a pipe for feeding fuel to an internal combustion engine; a housing interposed in said pipe and communicating therewith; valve means for shutting off the flow of fuel through said pipe; a gear revolubly mounted adjacent to said valve; a second gear meshing with said first named gear and operatively connected with said valve; said first named gear being provided with a socket for the insertion of a key for rotating said valve; guard means through which an operating key passes for engagement with said gear; means for automatically engaging said valve when same is rotated in one direction to hold same open; and means for releasing said holding means.
14. In combination, a pipe for feeding fuel to an internal combustion engine; a housing interposed in said pipe and communicating therewith; valve means adapted to slidably engage the inner periphery of said housing for shutting off the flow of fuel through said pipe; a gear revolubly mounted adjacent to said valve; a second gear meshing with said first named gear and operatively connected with said valve; said first named gear being provided with a socket for the insertion of a key for rotating said valve; a slotted key barrel revolubly mounted in front of said first named gear; and a
- notched guard in fixed position between the barrel and said first named gear; and means for automatically engaging said valve when same is rotated in one direction to hold same open; and means for releasing said holding means.
15. In combination, a pipe for feeding fuel to an internal combustion engine; a housing interposed in said pipe and communicating therewith; a shaft in said housing; arms pivotally mounted on said shaft and connected to a valve; a gear wheel mounted on inner side of one of said arms; a gear wheel meshing with said first mentioned gear wheel adapted to rotate said valve; and key operated means for imparting movement to said last named gear wheel.
16. A device of the class described comprising a housing, having a port therein; a segmental valve slidably engaging the inner periphery of said housing for closing said port; and means mounted in said housing, operable by a key, to move said valve for opening said port.
17. A device of the class described comprising a housing, having a port therein; a valve slidably engaging the inner periphery of said housing for closing said port; means mounted within said housing operable by a key for moving said valve to open said port; and spring held means engaging said valve to retain the same in open position.
18. A device of the class described comprising a housing, having a port therein; a spring operated valve slidably engaging the inner periphery of said housing and adapted in one position to close said port; and means, operable by a key inserted into said housing, for moving said valve to open said port; and means for engaging said valve for retaining the same in said open position.
19. A device of the class described comprising a housing, having a port therein; a valve slidably engaging the inner periphery of said housing and normally closing said port; means mounted in said housing for moving said valve for opening said port; a pin projecting into the interior of said housing and adapted to engage said valve when said port is open; and resilient means cooperating with said pin for retaining the same in valve engaging position.
20. A device of the class described, comprising a housing having a port therein; a valve slidably mounted in said housing for closing said port; means for locking and unlocking said valve; means for mounting said valve to swing about the longitudinal axis of said housing; and means normally retaining said valve in sliding contact with the inner periphery of said housing.
21. A device of the class described, comprising a cylindrical housing having a port

in the side wall portion thereof; a segmental valve mounted in said housing and rotatable about the longitudinal axis thereof; means for locking and unlocking said valve; and means for adjusting said valve toward and from the wall of the housing to compensate for wear.

22. A device of the class described, comprising a cylindrical housing having a port in the side wall portion thereof; a valve in said housing; adjustable arms mounted on said valve and extending inwardly therefrom; means for pivotally mounting said arms to swing about the longitudinal axis of said housing; and means for locking and unlocking said valve.

23. A device of the class described, comprising a cylindrical housing having a port in the side wall portion thereof and having a slot in the wall portion adjacent to said port; a valve movable about the inner face of said housing for closing said port; a second valve in said slot adapted also to be moved into and out of operative position with respect to said port; means for moving said valves in unison; and means for locking and unlocking said valve.

24. A device of the class described, comprising a cylindrical housing having a port in the side wall portion thereof and having a slot in the wall portion adjacent to said port; a valve movable about the inner face of said housing for closing said port; a second valve in said slot adapted also to be moved into and out of operative position with respect to said port; yielding means interposed between said two valves for pressing said second valve outwardly with respect to the housing; means for moving said valves in unison; and means for locking and unlocking said valves in said housing.

25. A device of the class described, comprising a cylindrical housing having a port in the side wall portion thereof and having a slot in the wall portion adjacent to said port; a valve movable about the inner face of said housing for closing said port; a second valve in said slot adapted also to be moved into and out of operative position with respect to said port; connections between said two valves serving to apply a yielding outward pressure upon said second valve and serving also to cause the two said valves to move in unison for opening and closing said port; resilient means normally holding said valves in operative position; key operable means for moving said valves to inoperative position; and retaining and releasing means for said valves.

26. A device of the class described, comprising a housing having a port in the side wall portion thereof and having a slot in the wall portion adjacent to said port; a valve movable about the inner face of said housing for closing said port; a second valve

in said slot adapted to be moved into and out of operative position with respect to said port; connections between said valves serving to apply a yielding outward pressure upon said second valve and serving also to cause the said valves to move in unison for opening and closing said ports; and means for locking and unlocking said valves.

27. A device of the class described including a housing having a port, there being a slot in the wall portion adjacent to said port; a valve movable about the inner face of said housing for closing said port; a second valve mounted in said slot and adapted to be moved into and out of operative position with respect to said port; connections between said valves so as to cause the same to move in unison; means normally urging said valves to closed position; means for engaging said valves when moved to open position; and means for releasing said engaging means.

28. In combination, a conduit for feeding fuel to an internal combustion engine; a valve for shutting off the flow of fuel through said conduit; a gear revolvably mounted adjacent to said valve; a second gear meshing with said first named gear and operatively connected with said valve; said first named gear being provided with means for the insertion of a key for rotating said valve; means normally urging said valve to closed position; means for engaging said valve when the same is turned to open position; and means for releasing said engaging means.

29. In a fuel controlling means for preventing the operation of an internal combustion engine, comprising a valve casing, there being aligned ports in said casing; a valve rotatably mounted in said casing and resiliently held in contact with the side walls of said casing; and means arranged to engage said valve for holding said valve in open position but permitting said valve to close upon being disengaged therefrom.

30. In a fuel controlling means comprising a valve casing; a valve mounted in said casing for preventing the passage of fuel therethrough; means arranged in the path of said valve for holding said valve in position to permit said passage but permitting said valve to close said passage upon being removed from the path thereof; and means for yieldably holding said valve in contact with the walls of said casing.

31. In a valve the combination with a casing open at one end, there being ports formed in said casing; means arranged in said casing for closing said ports; a closure member for said opening; and means for automatically locking the closure member against removal.

32. In a valve the combination with a casing open at one end and a member arranged in said casing for preventing com-

munication through said valve, of a closure member for said opening, there being recesses formed in the walls of said casing; and pawls carried by said closure member adapted to engage said recesses for preventing the removal of said closure member.

33. In a fuel controlling means for preventing the operation of an internal combustion motor, including a casing open at one end, there being a port formed in said casing; valve means in said casing for closing said port; means normally urging said valve to closed position; means for engaging said

valve when turned to open position; means for releasing said engaging means; a closure member for the open end of said casing; and means for automatically locking said closure member to prevent the removal thereof. 15

In testimony whereof I have signed my name to this specification in the presence of two subscribing witnesses.

WALKER E. MARSHALL.
